UNITED STATES PATENT OFFICE.

BERT S. SHERIDAN, OF CLEVELAND, OHIO.

AIR-HEATING FURNACE.

1,242,992.

Specification of Letters Patent.

Patented Oct. 16, 1917.

Application filed December 20, 1916. Serial No. 138,116.

To all whom it may concern:

Be it known that I, BERT S. SHERIDAN, citizen of the United States, residing at Cleveland, in the county of Cuyahoga and State of Ohio, have invented certain new and useful Improvements in Air-Heating Furnaces, of which the following is a specification.

My invention relates to air-heating furnaces, and the object of the invention is to provide an air-heating furnace with a gas burner of novel construction and to install the burner in a particular way to produce highly efficient heating results, all as hereinafter shown and described and more particularly pointed out in the claims.

In the accompanying drawings, Figure 1 is a side view and vertical section of an air-heating furnace embodying my invention. Fig. 2 is a front elevation and sectional view of the furnace, and Fig. 3 is a cross section on line 3—3, Fig. 1. Fig. 4 is an enlarged sectional detail of the ruffle plate and mouth end of the gas burner.

The introduction of gas into many communities induces the residents to convert their solid-fuel furnaces into gas-burning furnaces, but to change the ordinary air-heating furnace and fire-pot and grate, or to install a gas burner in lieu of the firepot or grate, is an expensive proceeding, generally inefficient in results, and wasteful of gas. My concept is to utilize the ordinary air-heating furnace without making a single change therein and install a gas-burner or pair of gas-burners in the ash-pit beneath the grate of the furnace, and relating them in a particular way so that a blow-pipe flame will be directed and spread against the cast-iron walls of the ash-pit at the very bottom of the furnace directly adjacent the air-intake ducts. In this way I utilize the base of the stove within the drum of the furnace as the heat-transmitting medium and reserve the fire-pot for solid fuel and for which the fire-pot is especially constructed, being of relatively greater thickness or provided with an extra lining as compared with the base of the stove. Quick and efficient radiating results are only obtainable by using relatively thin radiating walls, and the cast-iron ash-pit walls of the ordinary air-heating furnace are of this kind. Consequently, by arranging gas burners in the ash-pit to direct the flame against the side walls thereof and transforming the pit into

a combustion chamber I utilize the gas flame to the very best advantage and at the least expense, while the products of combustion are still compelled to travel through the fire-pot and usual discharge channels, and the fire-pot may still be used to burn solid materials.

As shown, the furnace consists of a drum or casing 2 inclosing a furnace made of cast-metal sections, comprising a base or ash-pit, section 3 having vertical walls 4 and an open front 5, and a superposed fire-pot 6 and dome section 7 having a stoking entrance or door 8 and a draft flue and discharge pipe 9 connection 10 extending through the casing 2. The fire-pot 6 is provided with suitable grate-bars 10 for burning solid fuel, and the bottom of the furnace has air intake ducts 12 at its bottom and the top of casing 2 has a number of discharge openings 11 for air-distributing pipes 13, as usual. In fact, the furnace as detailed is representative of the air-heating furnaces found in general use for burning coal and other solid fuels. To convert this furnace for burning gaseous fuel as well as solid fuel, I place a pair of gas burners within the ash-pit section 3, one opposite each side wall and near the bottom thereof. Each burner consists of a tube 15 having a separate flaring head 16 affixed upon the outer end thereof by a set screw 17 and connected to the gas nipple 18 of an angle valve 19 on the gas supply pipe 20. An apertured disk 21 at the front of head 16 serves to regulate intake of air and the mixing of air with the gas issuing from nipple 18, and the combustible mixture is ejected from the mouth or inner end of the tube 15 against the ruffle-plate 22 affixed to the said tube by screws or other means, see Fig. 4. The said ruffle plate 22 is a substantially flat member having transverse ribs 23 over its surface and disposed opposite the mouth of the tube and also inclined upwardly relatively to said mouth, and the said ribs or corrugations 23 extend on straight parallel lines transversely of the open end of said tube to ruffle the gaseous mixture and produce a spreading flame and complete combustion. Moreover, the inner ends of the burner tubes are placed relatively near the cast-iron side walls 4 of the ash-pit 3, and the said ruffle or mixing plates are projected toward said walls with an upward trend or inclination so that the flame therefrom or from the gas dashed and spread

thereon will be directed upwardly as well as transversely. The angular relations of the said plates to the side walls 4 is illustrated in Fig. 2, and the degree of angle and direction of the flame may be changed by rotary adjustment of the plates on rotating the burner tube 15 more or less in the head 16 upon releasing the set screw 17, and such adjustments may thus be conveniently 10 effected from the front of the furnace without removing the burners from the ash-pit.

By using a pair of gas burners of the kind and in the way described, any ordinary air-heating furnace having an ash-pit and 15 fire-pot for solid fuel may be converted into a practical gas-burning furnace by merely inserting said burners through the open ash-pit door, and by using a set of angle valves 19 in swiveled or rotatable screw-connection 20 with suitable fittings 24 on supply pipe 20, each burner tube may be moved or swung laterally in a horizontal plane and set on parallel or diverging lines to fit narrow or wide ash-pits and to place the mouth ends of 25 the burners at the proper and best working distance from the side walls 4. These ash-pit walls are thinner generally than the fire-pot walls and the impinging flames from burners 14 heat them red very quickly, and 30 the heat is radiated at the extreme bottom of the furnace where the cold air enters thereinto from the air ducts 12, thus utilizing the full length of the stove from base to dome for air heating purposes, because the 35 products of combustion from the burners also rise and pass between the grate bars

and through the fire-pot and usual channels to the discharge pipe 9.

It will be noticed that the ruffle plate 22 is substantially flat and gradually widened 40 outward and so set as to extend across the open end of the tube 15 at an angle of about 45 degrees and so that all the gas will be dashed or driven against the same and broken up and mixed so as to make the combustion complete.

What I claim is:

1. A hot air furnace having a fire-pot for solid fuel and a walled ash-pit below the same, in combination with a separate gas 50 burner tube adapted to be projected into said ash pit and having a transversely corrugated and flaring dash plate in inclined position across the end of said tube and adapted to direct the flame laterally against 55 the wall of said ash pit.

2. A hot air furnace adapted to use solid fuel and having a walled ash-pit in its bottom, in combination with a set of gas burner tubes projected into said ash-pit and having 60 each a ruffled and flaring dash plate for the gas at its end, said plate starting immediately at the end of the tube and extending at an upward and outward inclination across said end to a plane above the same, and 65 means to rotate said tubes axially to direct the flame against the wall of the ash pit.

Signed at Cleveland, in the county of Cuyahoga, and State of Ohio, this 16th day of December, 1916.

BERT S. SHERIDAN.
